UNITED STATES PATENT OFFICE

JAMES D. BOLTON, OF LOS ANGELES, CALIFORNIA

CAN OPENER

Application filed March 7, 1930. Serial No. 434,139.

This invention aims to provide a can opener having a novel form of lifting tongue for raising the portion of a can which has been cut loose by the opener.

5 Another object of the invention is to provide a novel form of handle for the cutting blade.

It is within the province of the disclosure to improve generally and to enhance the 10 utility of devices of that type to which the present invention appertains.

With the above and other objects in view, which will appear as the description proceeds, the invention resides in the combination and arrangement of parts and in the details of construction hereinafter described and claimed, it being understood that changes may be made in the precise embodiment of the invention herein disclosed, without 15 20 in the scope of what is claimed, without departing from the spirit of the invention.

In the accompanying drawings:—

Figure 1 shows in top plan, a device constructed in accordance with the invention;

25 Figure 2 is a longitudinal section wherein parts appear in elevation; and

Figure 3 is a transverse section on the line 3—3 of Figure 2.

The can opener forming the subject matter 30 of this application is made of metal throughout, and may be a one-piece structure. It comprises a curved blade 1, of approximately circular form in top plan, as shown in Figure 1, the blade 1 having free ends 2, and having 35 downwardly converging cutting edges 5 defining an entering point 3. A lifting tongue 4 is struck inwardly from the blade 1 and is located directly above the point 3, the tongue 4 extending upwardly, and slanting inwardly. The tongue 4 preferably is of rectangular outline, and has an upper edge 6 of appreciable length, disposed at right angles to the axis of the tongue, the tongue being 40 45 of common width from end to end.

Because the tongue 4 is of a common width from end to end, it is well adapted to withstand the hard use to which it is subjected, the tongue 4 being much more permanent and 50 lasting than would be a pointed tongue. The

function of the tongue 4 will be made manifest hereinafter.

The handle of the can opener may be made in any desired way. Preferably, however, it includes a top strip 7 joined integrally at 8 55 to the upper edges of the blade 1, above the entering point 3. The top strip 7 is contracted at 9 and folded at 10 to form a grip 11 which is of inverted trough-shape, the side walls of the grip being brought into contact 60 with each other as shown at 15 in Figure 3. The top strip 7 has laterally-prolonged, outwardly extended arms 12 which are bent upon themselves at 16 to form underlying, inwardly-extending fingers 14 which rest on the 65 upper edge of the blade 1, near to the free ends 2. The general construction of the handle is such that it can be made at trifling expense, an exceedingly strong structure resulting.

In operation, the entering point 3 of the blade 1 is forced down into the top of the can and a piece is cut out from the top of the can, the space between the ends 2 of the blade 1 permitting a part of the can top to remain 70 75 as a hinge, so that the cut-out portion can be closed up again, if desired. After the entering point 3 has been forced down into the can top to the desired extent, the grip 11 is swung down, the tool working like a lever, 80 and the tongue 4 engaging beneath the severed part of the can top, to swing the severed part of the can top open.

Having thus described the invention, what 85 is claimed is:—

A can opener fashioned from a single piece of metal, formed into a curved blade having free ends and supplied at its lower extremity with an entering point located diametrically opposite to its free ends, the blade being provided with means for lifting the portion of a can which is severed by the blade, there being an inwardly extended top strip connected at one end to the upper edge of the blade directly above the entering point, the top strip 90 being contracted and folded together transversely, at a point adjacent to the free ends of the blade, to form a handle of unequal transverse dimensions, the longer transverse dimension of the handle being at right angles 95 100

to the plane defined by the top strip, the top strip having oppositely-projecting lateral arms which are bent upon themselves to form underlying, inwardly extended fingers that 5 rest on the upper edge of the blade near to the free ends thereof.

In testimony that I claim the foregoing as my own, I have hereto affixed my signature.

JAMES D. BOLTON.
